UNITED STATES PATENT OFFICE.

MICHAEL J. MULLARKEY, OF DANVILLE, ILLINOIS, ASSIGNOR OF ONE-THIRD TO J. C. RATHBURN, ONE-THIRD TO C. J. MCGEE, AND ONE-THIRD TO O. W. OLSON, ALL OF DANVILLE, ILLINOIS.

OIL-BURNER.

1,186,820.

Specification of Letters Patent. Patented June 13, 1916.

Application filed September 23, 1915. Serial No. 52,242.

To all whom it may concern:

Be it known that I, MICHAEL J. MULLARKEY, a citizen of the United States, residing at Danville, in the county of Vermilion and 5 State of Illinois, have invented certain new and useful Improvements in Oil-Burners; and I do hereby declare the following to be a full, clear, and exact description of the invention, such as will enable others skilled 10 in the art to which it appertains to make and use the same.

This invention relates to oil burners, and has for one of its objects the provision of a duplex oil burner which is capable of being 15 readily attached to or positioned within kitchen ranges, cooking stoves, heating stoves, furnaces, grates, etc., burning either wood or coal.

Another object of this invention resides 20 in the provision of a duplex oil burner provided with a novel form of deflector plates and their mountings for deflecting the flames of the respective burners in any desired direction within the range or stove.

25 A further object of this invention resides in the provision of a novel base for supporting and maintaining in fixed relation to each other the conduit pipes of the burners.

A still further object of this invention resides 30 in the provision of a duplex oil burner which is capable of being attached to or detached from ranges, stoves, etc., which is simple in construction, efficient and durable in purpose, and which can be manufactured 35 and sold upon the market at an exceedingly small cost.

These and other objects will more fully appear as the nature of the invention is more clearly understood from the following 40 specification, the subject-matter of the claims, and the construction illustrated in the accompanying drawings, in which,

Figure 1 is a vertical sectional view through the fire box of a stove or range 45 showing my invention as the same would appear when positioned within the stove or range, Fig. 2 is a vertical sectional view of one of the deflector plates and its support, taken on line 2—2 of Fig. 1, Fig. 3 is an end 50 view of one of the burners, the duplex burner feed pipes and the supporting base therefor, partly in section, showing another form of deflector plate and the mountings therefor, and Fig. 4 is a bottom plan view of 55 the deflector plate and its mountings shown

in Fig. 3, showing the attaching portion of the burner pipe as partly broken away.

For the sake of clearness and convenience, I will describe my invention as being applied to the fire box of a kitchen range, however, 60 I do not restrict my invention to this exact application, as the invention is equally adaptable to other types of stoves such as cooking and heating stoves burning either wood or coal, and also to fire-place grates. 65

Referring to the drawings, 1 denotes the top of the fire box of the range, 2 the back wall, 3 the front wall having the door opening 4 formed therein, 5 the front grate within the fire box, 6 the bottom grate, and 7 70 the ash pit beneath the bottom grate 6. Dividing the fire box from the oven of the range is the partition wall 8, and between the upper edge of the partition wall 8 and the top 1 is the draft flue 9.

75 The duplex oil burner comprises two individual burners fed by an oil tank 10 having the vertically disposed depending supply pipe 11 provided adjacent its lower end with the main valve 12, and secured upon the lower end of the supply pipe 11 below the main valve 12 is the front individual burner valve 13. Beneath the front individual burner valve 13 is the rear individual burner valve 14, the valves 13 and 14 being connected together by the stub pipe 15.

80 Connected to the front individual burner valve 13 is the front individual burner feed pipe 16, this pipe extends horizontally for a portion of its length and is curved upwardly and outwardly as at 17, providing the upper horizontal vaporizing portion 18, and is then curved downwardly and inwardly as at 19 and terminating in the lower horizontal portion 20, upon the end of which 85 is provided the cap 21. In the upper surface of the horizontal portion 20 and adjacent the cap 21 is formed the aperture 22, this aperture 22 providing the burner outlet, and secured upon the lower horizontal portion 100 20 beneath the aperture or burner outlet 22 is the starting cup 23. This construction forms the front individual burner.

Connected to the rear individual burner valve 14 is the rear individual burner feed 105 pipe 24, this pipe also extends horizontally for a portion of its length and is curved upwardly and outwardly as at 25, providing the upper horizontal vaporizing portion 26, and is then curved downwardly and in- 110

wardly as at 27 providing the lower horizontal portion 28, upon the end of which is provided the cap 29. In the upper surface of the horizontal portion 28 is provided the aperture 30 which forms the rear burner outlet, and secured upon the lower horizontal portion 28 beneath the aperture or burner outlet 30 is the starting cup 31. This construction forms the rear individual burner.

The main horizontal portions of the burner feed pipes 16 and 24 are of different lengths in order that the rear individual burner may be properly positioned in alignment with and behind the front individual burner, the burner feed pipe 16 being positioned above the burner feed pipe 24, and to provide for this positioning of the feed pipes 16 and 24 and the individual burners, the upwardly and outwardly curved portion 25 of the pipe 24 describes a greater arc than the upwardly and outwardly curved portion 17 of the pipe 16.

For supporting and maintaining the burner feed pipes 16 and 24 in their proper spaced relation, a pair of oppositely disposed base blocks 32 and 33 are provided. The blocks have the upwardly extended portions 34 and 35 respectively, and formed within their meeting faces are the upper semi-circular recesses 36 and 37 in which is seated the front individual burner feed pipe 16, and also the lower semi-circular recesses 38 and 39 in which is seated the rear individual burner feed pipe 24. These base blocks are placed face to face with the burner feed pipes 16 and 24 seated one above the other within the recesses 36 and 37 and 38 and 39 respectively, and secured together through the medium of the bolt 40 which passes transversely through the registering apertures formed in the upper extended portions 34 and 35 of the base blocks 32 and 33 at a point midway between the burner feed pipes 16 and 24, as clearly shown in Fig. 3 of the drawings.

To provide for the deflection of the flames from the burner outlets 22 and 30, I provide the individual burners with the deflector plates 41, the deflector plates 41 are double convex-shaped and have formed in their under sides and centrally thereof the deep hemispherical recesses 42, the walls of which frictionally engage the upper portion of the spherical heads 43 of the Z-shaped brackets 44, which are provided at their lower ends with the collars 45 which embrace the upper horizontal vaporizing portions 18 and 26 of the individual burners respectively, adjacent the bends 17 and 25 of the burner feed pipes 16 and 24, the collars 45 being adjustably secured upon the horizontal vaporizing portions 18 and 26 through the medium of the set screws 46.

In Fig. 3 is shown another form of a deflector plate designated 47, this plate is simi-

lar in construction to the plate 41, excepting, that instead of forming the spherical recess 42 therein, the plate 47 is provided with the diametrically disposed semi-circular groove 48 in which is seated the upper horizontal vaporizing portion 18 or 26 respectively of the individual burners formed at the end portions of the pipes 16 and 24, as the case may be, the portions 18 and 26 being surrounded by the eye 49 of the eye-bolt 50, the eye 49 having the upper portion thereof seated in the semi-circular recess 51 formed centrally in the under side of the plate 47, the recess 51 extending transversely across the groove 48, and extending upwardly from the central point of juncture of the groove 48 and the recess 51 is the aperture 52 through which the threaded end of the bolt 50 extends, the end of the bolt projecting above the upper surface of the plate 47 and having threaded thereon a suitable nut which binds upon the upper surface of the plate 47, thus retaining the plate 47 in its respective adjusted positions upon the horizontal vaporizing portion 18 or 26 of the respective individual burners.

While I have here shown my invention as including only two burners, which I will now broadly term burners for the purpose of further description, I desire it to be understood that my invention is not limited to this exact number, for by dispensing with one of the burners and the valve therefor, a single burner and valve may be used, or by adding additional burners and the valves therefor, my invention may include any number of burners and valves desired or necessary to meet the exigencies of the case. Moreover, the burners may or may not be supplied with the deflector plates as shown, but I deem the use of the plates as exceedingly advantageous for deflecting the flames of the burners to any point within the fire box of the range or stove to which the same may be attached in order to attain the greatest units of heat at a given point, as well as to economize in fuel.

The plate 41 shown in Fig. 2 and the manner of mounting the same permits a universal movement of the plate for directing the flame at any point within the stove, and may be operated at will by the use of a poker or other implement, this being easily accomplished due to the fact of the ball and socket or universal mounting of the plate 41. The plate 47 shown in Figs. 3 and 4 is only capable of a lateral swinging movement with respect to the burner, which may be either in a horizontal position, as shown in full lines or to the right or left directions, the plate being shown as positioned to the left only, as shown in dotted lines in Fig. 3, this adjustment of the plate 47 being accomplished by loosening the nut of the bolt 50, adjusting the plate 47 in the

desired position, and then screwing the nut firmly against the upper surface of the plate 47, whereby the binding action of the eye bolt 50 firmly secures the plate 47 in its 5 adjusted position.

Another feature of my invention resides in the construction of the burners out of a single piece of pipe of any suitable length, by bending one end of the pipe to a form 10 substantially the shape of the letter J, but extending the curved portion of the pipe farther inwardly and downwardly and forming a transverse orifice in the upper wall of the pipe adjacent its end and providing a cap upon the end of the pipe. This manner of forming the burners produces not only a simple and cheap burner, but an efficient vapor burner as well, as the 15 flame from the burner outlet 22 or 30 vaporizes the oil in the horizontal vaporizing portion 18 or 26 in its passage therethrough when the portion 18 or 26 has become sufficiently heated after the initial lighting of the burner outlet 22 or 30 as the case 20 may be.

Having now described my invention, what I claim as new and desire to secure by Letters-Patent, is:—

1. In a device of the class described, the 30 combination with a stove, and the fire box thereof, of a liquid fuel reservoir, a supply pipe depending from said reservoir, a plurality of burners connected to said supply pipe, each of said burners being formed of 35 a single piece of pipe having one of its ends curved upwardly and outwardly and thence downwardly and inwardly to provide an elongated horizontal feed pipe portion, a horizontal vaporizing portion, and a horizontal 40 burner outlet portion.

2. In a device of the class described, the 45 combination with a stove, and the fire box thereof, of a liquid fuel reservoir, a supply pipe depending from said reservoir, a plurality of burners connected to said supply pipe, each of said burners being formed of 50 a single piece of pipe having one of its ends curved upwardly and outwardly and thence downwardly and inwardly to provide an elongated horizontal feed pipe portion, a horizontal vaporizing portion, and a horizontal burner outlet, and a double convex-shaped deflector plate adjustably supported

upon the vaporizing portion of each of the burners above the burner outlet thereof. 55

3. In a device of the class described, the combination with a stove, and the fire box thereof, of a liquid fuel reservoir, a supply pipe depending from said reservoir, a plurality of burners connected to said supply 60 pipe, each of said burners being formed of a single piece of pipe having one of its ends curved upwardly and outwardly and thence downwardly and inwardly to provide an elongated horizontal feed pipe portion, a 65 horizontal vaporizing portion, and a horizontal burner outlet portion, a double convex-shaped deflector plate adjustably supported upon the vaporizing portion of each of the burners above the burner outlet 70 thereof, and a sectional base support embracing the feed pipe portions of said burners for supporting said burners in operative position.

4. In a device of the class described, the 75 combination with a stove, and the fire box thereof, of a liquid fuel reservoir, a supply pipe depending from said reservoir, a plurality of pipes connected to said supply pipe, each of said burners being formed of 80 a single piece of pipe having one of its ends curved upwardly and outwardly and thence downwardly and inwardly to provide an elongated horizontal feed pipe portion, a horizontal vaporizing portion, and a horizontal 85 burner outlet portion, a double convex-shaped deflector plate adjustably supported upon the vaporizing portion of each of the burners above the burner outlet thereof, a sectional base support embracing the 90 feed pipe portions of said burners for supporting said burners in operative position, said base sections comprising two blocks provided with semicircular recesses in their meeting faces for embracing the feed pipe 95 portions of said burners, and means projecting through said base sections for maintaining said feed pipe portions of said burners therebetween.

In testimony whereof I have signed my 100 name to this specification in the presence of two subscribing witnesses.

MICHAEL J. MULLARKEY.
